TACKLE BOX OR THE LIKE

Robert A. Jean, Jacksonville, Fla., assignor to
J. W. Lures, Inc., Jacksonville, Fla.

Filed June 2, 1975, Ser. No. 583,415

Term of patent 14 years

Int. Cl. D3—99

U.S. Cl. D87—1 R

FIG. 1

FIG. 2

FIG. 4

FIG. 5

FIG. 3

FIG. 6

FIG. 7

FIG. 8

FIG. 9

FIG. 10

FIG. 11

FIG. 12

FIG. 1 is a top plan view of a tackle box or the like showing my new design, the dividers shown in FIG. 6 being omitted through the transparent top for convenience of illustration;

FIG. 2 is a right side elevational view thereof;
FIG. 3 is a bottom plan view;

FIG. 4 is a front elevational view thereof;

FIG. 5 is a rear elevational view;

FIG. 6 is a perspective view thereof with the top in an open condition and the flexible handle in its outward condition;

FIG. 7 is a top plan view of the tackle box showing another embodiment of my new design with the cover being opaque and the bottom view being identical hereto;

FIG. 8 is a right side elevational view thereof;

FIG. 9 is a front elevational view thereof;

FIG. 10 is a rear elevational view;

FIG. 11 is a cross-sectional view taken along line 11-11 of FIG. 9; and

FIG. 12 is a view similar to FIG. 8 but turned 180° and with both covers in open condition.

I claim:

The ornamental design for a tackle box or the like, substantially as shown and described.
